MASSAGE

Reimar Pohiman, Berlin, Germany

Application May 25, 1939, Serial No. 275,763
In Germany May 25, 1938

2 Claims. (Cl. 128—24)

This invention relates to massage. It has been known for many years to employ massage for obtaining higher blood circulation, for reinforcing the muscle system and for removing lactic acid from the latter in the case of fatigue. Such massage has been carried out partly by hand and partly by the aid of apparatus, such as that known as a "vacuum cup" roller, which effect massage by the local action of rubber sucking elements and produce a higher blood circulation. In all such cases the massage takes place on the surface of the skin and its effect is limited to the superficial parts of the body. Moreover, the massaging forces are spread over comparatively large areas, so that the force per unit area is comparatively small and in consequence not very effective. Massage effects which are not only concentrated, but which also penetrate deep to below the skin are not obtainable by known methods.

It has already been proposed to employ ultra sound for treatment of the human body. Sound, particularly ultra sound, as already known, is a longitudinal vibratory movement of those parts of the medium which are excited by the sound wave. If one accordingly radiates the point of the human body to be massaged with ultra sound by placing an ultra sound generator in contact therewith, the ultra sound penetrates into the body and sets up vibrations in the tissue thereunder to a great depth. Sufficiently great energy could not, however, be applied in this known way, because during absorption the ultra sound energy is transformed into heat which becomes unbearable when attempts to use great energy are made.

In accordance with the present invention, however, the ultra sound generator of a massage apparatus, is built inside the striking apparatus of the kind used in known massage heads, and during treatment the ultra sound generator is not held stationary but is secured over the part to be treated. The operator can easily vary the energy radiated per unit area by moving the generator slowly or more rapidly over the part to be treated. The energy applied may thus readily be adapted to the comfort of the person under treatment. Such regulation of the energy has not been possible in the case of Röntgen, ultra-violet, or other radiations. This kind of treatment has the advantage that extraordinarily great ultra sound energies may be applied.

To enable particularly great local energy-density to be applied, the ultra sound generator can also be operated intermittently. This can be effected either by periodically de-tuning the ex-

citing electric alternating voltage, or by means of an interrupter device built into the electric exciting apparatus. It is found that a person under treatment can receive without any untoward effect intermittently applied energy at strengths which he could not endure when applied continuously. The depth to which the action penetrates may be regulated by adjusting the frequency of the ultra sound radiation, low frequencies being effective at greater depth than high frequencies. Action at depths of from two centimetres up to twenty centimetres may be so obtained. It is essential that each part treated by the ultra sound should be set into violent vibration even at great depths, and thus be subjected to strong compressive and tensile stresses, and that the effect should not be limited to regions near the surface as in the case of hand massage.

20 As closer researches have shown, the depth massage described has achieved wonderful effects in all illnesses such as rheumatism, sciatica, arthritis, which react to such treatment.

As researches have further shown, the method 25 of massage described is capable of rubbing into the skin substances which do not easily penetrate, such as ointments, medicines and cosmetics. Methods are already known to rub substances into the skin either by hard rubbing or by electrical means. The present method, however, 30 works in a different manner and enables substantially greater quantities of the substances to be rubbed into the skin. This is due to the different effects from those produced by the aforementioned methods, the skin pores being not only 35 completely obturated, as in the case of rubbing in where the depth penetration is limited to regions close to the skin, but owing to the hard compressive and tensile effects of ultra sound 40 waves, the pores of the treated part are enlarged, rendered elastic and the applied substance is emulsified at the same time in the expanded tissue by the sound pressure. This effect extends deeply into the tissue and thus greater quantities 45 of the applied substances are caused to penetrate, whereas hitherto, the upper layers of the treated part become at once super-saturated with the substance.

This effect is considerably enhanced by the 50 diathermic action of the ultra sound waves. This leads to the conclusion that the local diathermic effects of the ultra sound radiation may also be utilised; in the rubbing in of substances this effect plays a role in such a way that most ointments, cosmetics and the like become more fluid

when hot, when they have very much greater penetrating powers. This effect cannot be obtained by applying the cosmetics or the like in a heated state in the first instance, because such substances will take the body temperature when they reach regions close beneath the skin surface, whereas in the present case the heat effect, and thus the fluidity of the cosmetics or the like is maintained deep down under the skin surface. The present method is thus of particular importance to beauty specialists.

The invention is illustrated by the accompanying diagrammatic drawings of which:

Figure 1 shows in longitudinal section a supersonic massage head in which the oscillating generator is arranged in an insulating liquid;

Figure 2 shows schematically in longitudinal section another embodiment of a supersonic massage head in which the oscillating generator is arranged directly on the foil covering of the housing;

Figure 3 shows a supersonic massage head in longitudinal section in which a magnet striction transmitter serves as oscillating generator.

Figure 4 shows more precisely the formation of a supersonic massage head in which the oscillating generator is arranged in the same manner as in Figure 2.

Figures 5, 6, 7a, 7b, 8 and 9 are detail views of the arrangement in accordance with Figure 4.

As shown in Figure 1, a glass receptacle indicated at 1 is sealed by a ground part 2. The provision of a ground part permits easy removal of the internal equipment, and also enables to be taken into account the expansion of the liquid 9 during working. There are indicated at 3 conductors to the high frequency generator which delivers the required high frequency alternating voltage in the known manner. This alternating voltage is conducted to the electrodes 4 and 5. At 4 is a small air-filled chamber which is sealed in front by a thin metal foil 6. The chamber rests behind upon a ceramic insulator 13 and prevents the escape of the ultra sound radiation backwards so that the insulator 13 is protected against destruction by the ultra sound radiation. The ultra sound waves generated by a piezo quartz crystal 7 issue through the aperture 8 in the electrode 5 towards the front, by way of the surrounding medium 9, for example, xylol, and through the thin membrane 10, which is held by the retaining ring 11 and so into the human body indicated at 12. Should a substance as described above be rubbed in the body, it is first applied upon the part of the body to be treated and is disposed between 12 and the membrane 10 as a contact substance. In this connection it is desirable that a layer of this contact substance, which is as thick as possible, is between the body part to be treated and the massage head. In order that a sufficient layer thickness is obtained and the contact substance is not pressed away eventually through the massage head itself from the place to be treated means may be provided which hold the membranes at a small distance from the surface to be treated. Rounded off projections 29 arranged in the form of a crown around the foil may for example serve as such means, which projections may be provided on the screw nut 11 or 34 respectively holding fixedly the foil.

The example shown in Figure 2 works without liquid. At 13 are indicated ground steel plates which are disposed parallel to one another. At 14 are two piezo quartz crystals which are ce-

mented in place with their axes directed oppositely upon the thin steel foil 15, so that they oscillate in equal cycle. At 16 is indicated a housing. The conducting cable 3 is under the high frequency alternating voltage as in the previous case. The individual components of the oscillating body 13 and 14 are cemented together and the oscillating body itself is brought in contact with the body part to be massaged through the medium of a contact substance. Instead of the two quartz plates 14 illustrated, a plurality of thin quartz plates may also be incorporated between the steel plates 13 which are all cemented together in the way described above, so that in a certain degree a condenser with quartz dielectric is produced. If one cements alternate plates with their electric axes disposed in opposite directions, respectively, then they contract and expand simultaneously, and constitute an oscillating body which achieves great amplitudes with comparatively small voltages.

The massage head may be built employing either the electro dynamic or the magneto-striction principle. In Figure 3, 17 is a slotted nickel tube which is damped at 18 in an iron housing 19. On the one end is disposed a coil 21 tapped at 20, and on the other end is a coil 22 serving for direct current magnetisation. If one connects the leads 20, 23 and 24 appropriately with an electron tube arrangement, high frequency oscillations are generated which excite the nickel tube 17 to strong longitudinal oscillations, which pass through the plate 25 into the body 12. The magnetic flux circuit of the generated magnetic fields is closed through the iron housing 19 which is slotted to prevent eddy currents and to obtain a cooling action. An insulating screw plug 26 leads to the connecting cable. This arrangement also enables a contact substance to be used between 25 and 12. For longer use, a special cooling device can be provided.

Great losses may occur in transforming and transmitting the electric oscillating energy into ultra sound energy, and in transmitting the sound energy into the human body. The transmission of the high frequency alternating voltage into the ultra sound massage head presents special difficulties owing to the large partially capacitative and partially dielectric losses in the insulation of the connecting cable, also the required high insulation of the conducting cable substantially affects the mobility of the massage head.

In known massage apparatus, which do not work with ultra sound, these difficulties do not occur, as it is only a question of the transmission of high frequency of 50-100 cycles at small voltages, whilst in the case of massage apparatus in accordance with the invention, a frequency of approximately 510^5 - 510^6 cycles at a voltage up to 5,000 volts must be transmitted. The transmission of the generated ultra sound energy, with a minimum of losses, into the human body also causes difficulties because in consequence of the small ultra sound amplitude, thin air layers, membranes and any boundary layers of various solid sound transmitting mediums and cavitation of transmitting liquids weaken the intensity of radiation.

In accordance with the invention, the aforesaid losses may be almost if not entirely prevented by the fact that the place where the energy transformation takes place, particularly the place where the transformation of the low tension high frequency energy into the high volt-

age high frequency energy takes place, and the place where transformation of high frequency energy into ultra sound energy takes place are as close as possible to the place at which the ultra sound energy is to be applied or radiated. As in the case of ultra sound massage generally, only a small energy may be brought into the human body if destructive effects are to be avoided. The prevention of the energy losses achieved by the arrangement in accordance with the invention signifies the possibility of employing very small and convenient high frequency generators for the operation of ultra sound massage heads, which are, moreover, inexpensive in manufacture and in use.

In order that the transformation of high frequency energy into ultra sound energy shall take place as close as possible to the part to be treated, the ultra sound generator, particularly such as an oscillating quartz or an electrodynamic magneto-striction generator, contacts directly with the surface of the body to be treated. Ultra sound apparatus, specially for medical and biological examinations, have already been proposed which are fixed to a stand and are mounted near to the place to be treated, and allow a local ultra sound radiation. However, the ultra sound radiation in the case of such known apparatus, must permeate a thicker oscillation absorbing oil layer in which, moreover, cavitation occurs at high intensities; further in the case of the known arrangements, reflection takes place at the outlet foil. The whole reflections and other losses are prevented, in accordance with the invention, if the ultra sound generation takes place at the surface of the body to be treated.

In order to transform low tension high frequency energy into high voltage high frequency energy as close as possible to the place to be treated and so reduce losses in the connecting leads as much as possible, the high frequency transformer may in accordance with the invention be built within the ultra sound massage head itself, so that the transformation does not take place in the high frequency generator, but in the massage head.

A low tension cable is then used to connect the massage head with the high frequency generator, the dielectric and capacitative losses in such cable being small. Apart from this, there is another advantage that also the modifications of tuning due to the alteration of capacity consequent upon movement of the flexible cable are reduced.

If the oscillating quartz crystal is in direct contact with the body to be treated during the treatment, the quartz will oscillate in a completely undamped condition when running idle, that is to say, when the massage head is lifted temporarily from the body, and this will lead to its immediate destruction. In order to avoid it, a radiation load may be provided at its rear side which on the one hand may be as small as possible in order that, despite the damping afforded thereby, smallest possible energy is taken away during the treatment, the damping being just sufficient to protect the quartz from destruction. A plate may be cemented, as a load, to the rear side of the quartz, which plate serves advantageously at the same time as an electrode, or there may be oil as a radiation load behind the quartz.

Alternately, such load may be omitted and means may be provided to ensure that the full operating voltage is applied to the oscillatory quartz only when the massage head is in contact with the body to be treated. For example, by

contact of the massage head, or of the metal membrane closing the massage head, respectively, with the earthed patient through a resistance, the high potential of the high frequency generator may be so modified that only at this moment oscillations with substantial amplitude occur or particularly if one works with high frequency, the quartz may be so elastically mounted on the massage head that it is shifted by contact of the massage head with the body towards an electrode plate, so that the capacitative coupling of the quartz is increased, and that oscillations with corresponding amplitude will result.

Figure 4 shows a massage head in which the oscillating quartz 31 is cemented to an electrode 32 serving as a damping load during idle running and which electrode may consist, for example, of an aluminum alloy or of a steel. To the other side the quartz is cemented a foil, for example, a steel foil which is rigidly soldered to a ring 34 and is tensioned by screwing the latter on to the housing 35. In order that the cementing of the quartz to the electrode does not fail when heated during working, the quartz may be held by a spring device 36 against the membrane 33. The spring 36 consists of an annularly bent leaf spring which is compressed from two diametrically opposed points. The spring device 36 is separated from the core 40 by an insulator. This ring 36 consists of a thin steel band and is bent into an ellipse as a result of the compression. The ring is attached to the insulator located between spring device 36 and core 40, in order that the spring device 36 is electrically insulated from the grounded transformer core 40. One of the conductors 30 passes from coil 41 to the insulated spring device 36, while the other conductor leads to ring 34 or membrane 33. The spring device is adapted to provide a good contact with damping plate 32 and furthermore, it should prevent the cement which softens as a result of the heat, from becoming detached between 31 and 32. Conductor 30 is soldered to the spring device 36. For transforming the low tension high frequency energy from the cable into high voltage high frequency energy, a transformer is disposed in the massage head itself which consists of a core 40 of high frequency iron, of a secondary winding 41 and a primary winding 42; the primary winding may constitute either a part or the whole of the inductance of the oscillating circuit which is readily possible in the case of high frequencies; otherwise the massage head has to be inconvenient in form or is too heavy. In this way the high voltage energy is initially produced in the immediate vicinity of the quartz and only very short leads 30 are required to conduct the high voltage to the quartz, whilst a substantially smaller voltage prevails in the connecting cable 3 to the massage head, so that in addition the losses in the cable are small and a cable of ample flexibility and low insulation may be employed.

Instead of a plate cemented to the quartz as a radiation load, a fluid radiation load, for example, oil, may be employed also at the rear of the quartz, as shown in Figure 5. In this embodiment the quartz 31 is again cemented to the foil 33 which is tensioned by the ring 34 in the same way as in the example shown in Figure 4.

Owing to the heat resulting from the absorbed ultra sound radiation, the liquid has a tendency to expand in the massage head during working. In view of this a valve is provided in the arrangement illustrated in Figure 1. In an apparatus resting upon and secured to a support, which

apparatus is locally rigidly mounted, the discharged liquid may be collected easily in the rising pipes or the like. In a message head which is moved during treatment and which operates in any position, such outlet valves may be very inconvenient; in particular there may be a danger of clothes and linen being soiled by escaping oil and that upon subsequent cooling of the massage apparatus when the oil is again contracted, air bubbles may penetrate into the interior which may cause electric discharge by arcing, and of other troubles. In order to allow the oil to expand without risk of its escaping from the massage head, in accordance with the invention, the massage head itself may be closed in an oil- or air-tight manner and for equilibrium a large air bubble 38 (see Figure 6) may be formed. To prevent this air bubble reaching the quartz at 36 which might result in the destruction of the quartz, a protecting ring 37 is provided which is so formed, preferably of conical shape, that the air bubble 38 cannot reach the opening of the ring 37 whatever the position of the massage head. Thus gases which are released in the space between the protecting ring and quartz by cavitation escape through the opening of the ring 37 from this space when the message head is in a vertical or approximately vertical position and may be united with the air bubble 38; but no gases may return to this space. In order to prevent failure of the cementing of the quartz due to heat evolved during working, a spring device 36 pressing the quartz against the membrane 33 may be provided here as in the case of Figure 4.

In order to improve the sound transmission to the human body and to easily adapt the massage apparatus to various requirements, transmitting members may be provided, which may be mounted, as illustrated in Figures 7a, 7b and 8, upon the massage head by means of the arms 45, for instance through a bayonet joint.

The transmitting member illustrated in Figure 7a consists of a block 43 of a good sound conducting material, for example, of glass or aluminium. Assuming the device to be applied to human tissue in which the velocity of sound is approximately 1500 metres per second, and that the velocity of sound in the material of the transmitter member is 5,000 metres per second, there will be a sound optical refractive index n , i. e.,

$$\frac{v_1}{v_2}$$

equal to 3.3 and the focal distance f of the transmitter member acting in the manner of a lens, i. e.,

$$\frac{r}{n-1}$$

where r is the radius of curvature and is equal to 11.5 centimetres, of 5 centimetres will be obtained. By corresponding selection of the radius of curvature r the ultra sound radiation may be focussed to any desired depth. In Figure 7b is illustrated another transmitter member, the body of which consists also of a good sound conducting material and which is so formed that the ultra sound radiation is strongly concentrated upon the surface of the body to be treated. In order to obtain an increased effect, it is advantageous to tune the transmitter members as regards their length in regard to the frequency. Transmitter members for ultra sound generators are already known. However, these known transmitter members cannot be brought into di-

rect contact with the quartz employed and consequently there is a double reflection of the ultra sound radiation, and in consequence great losses by reflection. Moreover, known transmitter members do not have any focussing effect and they are not tuned as regards their length to the natural frequency of the quartz.

Owing to the good energy transmission, great heating of the surface of the body to be treated takes place. In order to compensate for this, the transmitter members may be provided as illustrated in Figures 8 and 9 with cooling means, in order to cool through the cooling thereof the surface of the body to be treated. The arrangement illustrated in Figure 8, which may be mounted upon the message head, has transmitter members in accordance with Figures 7a and 7b attached thereto by means of a bayonet joint and the member 43 may be surrounded with a water cooling space 44. The member 43 may be tuned in regard to the frequency and effects through the direct mounting upon the quartz 31 an excellent low loss sound conductor. In the case of the transmitter member shown in Figure 9 the entire space 46 is traversed by the cooling liquid. In this way a very intensive cooling is obtained. This arrangement in some circumstances, however, has the disadvantage that cavitation may occur in the case of water containing air, and in consequence the energy transmission will be adversely affected.

In Figure 5 is illustrated a further form of the ultra sound generator in which to avoid the necessity of employing energy absorbing damping load, the quartz 31 is stuck to a springy elastic membrane 33, so that in applying the massage head to the surface of the body to be treated, the quartz is shifted towards the electrode 47. In this way, the capacitative coupling is increased and the energy transmitted is accordingly greater. In this arrangement quartz can never oscillate undamped when running idle, as the latter is only excited to oscillations when damping already exists due to the pressure upon the head of the electrode, whilst when this contact damping is removed, the oscillation of the quartz and the voltage amplitude drops automatically so low that splintering of the quartz is avoided. At the same time, however, energy losses caused by the damping load during working are avoided.

A particularly favourable transmission of the energy upon the place of the body to be treated is obtained if the frequency of the ultra sound radiation is so chosen that the radiation up to the depth of penetration required to be reached, is just absorbed. As the detailed measurements by the inventor about the ultra sound absorption in human texture have established, the penetrating depth for which the radiating intensity lowers is about 4.9 cms. at 800 kilocycles, 1.5 cms. at 2400 kilocycles and so on. For treatment of deep parts, for example, in the case of sciatica and the like, it has been found extraordinarily favourable to employ a low frequency; for treatment of skin diseases and the like, a high frequency. In order to be able to change over from higher to lower frequency and vice versa without interchanging the oscillating quartz, the electric apparatus is advantageously so formed that by simply shifting a switch lever, the apparatus may be changed over precisely to the fundamental frequency or to a harmonic frequency of the quartz or other ultra sound generator. In this way it is possible readily to employ the same apparatus for deep or surface action.

I claim:

1. A massage apparatus comprising a housing, a diaphragm closing an aperture in the front of said housing, means disposed within said housing to impart to said diaphragm vibrations of super-sonic frequency and a block of vibration-trans-mitting material disposed in front of said dia-phragm to transfer the vibrations from the dia-phragm to the body being massaged, said block being provided with a hollow opening there-
through whereby a cooling liquid can be circu-

lated therethrough to produce the tension of the block when the apparatus is in use.

2. A massage apparatus comprising a housing, a diaphragm closing an aperture in the front of said housing, means disposed within said housing to impart to said diaphragm vibrations of super-sonic frequency and a block of vibration-trans-mitting material in lens form disposed in front of said diaphragm to transfer the vibrations from the dia-phragm to the body being massaged.

REIMAR POHLMAN.
